Application May 6, 1957, Serial No. 46,034

Term of patent 14 years

(Cl. D67—4)

FIG. 4

Fig. 1 is a view in front elevation of a water cooler embodying my new design;

Fig. 2 is a side elevation of the water cooler shown in Fig. 1, as observed from the right thereof;

Fig. 3 is a top plan view of the water cooler shown in Fig. 1; and

Fig. 4 is an enlarged vertical cross-sectional view through the center of Fig. 1 from front to rear with the elements on the top shown in broken lines in Figs. 1, 2 and 3 omitted for convenience of illustration only.

The side of the illustrated water cooler, as observed from the left of Fig. 1, is similar to that shown in Fig. 2.

The dominant features of the design reside in the portions shown in full lines.

I claim:

The ornamental design for a water cooler, as shown and described.
